Breech-Loaders

1875.
DIVISION.

1/2m

John Thomson & Hall

Patented May 21- 1871.

Improvements, &c. or
Improvements
Invented May 2d 1861.

This invention consists of a Receiver, moveable by sliding either perpendicularly or laterally or endwise, or else moveable on an axis either perpendicularly or laterally, & connected with the Barrel by a piece or pieces of metal. — The receiver is moved either by means of a spring, lever or screw, & is kept in its place when shut down, or brought in a line with the barrel, by means of a catch, lever screw or bolt. — It is applicable to every species of fire arms. — Its advantages are dispatch & convenience in loading, in every situation, either lying on the ground, sitting, standing or on horseback.

More particular description

The receiver consists of a cavity or chamber in solid metal, or a chamber of one metal may be let or screwed into another metal. — This cavity or Chamber for containing the charge may either be conical, cylindrical or otherwise. — The muzzle of the receiver should either be arched perpendicularly from top to bottom, making a curve, whose center is the axis on which the receiver moves, or be cut slantingly so that its upper end may be a tangent to the lower part of the curve. —

The Stock may either be let into the solid metal of the Chamber or attached to it, or placed on the side of the piece as usual, taking care to form the parts correspondently. — The Chamber, receiver, or cavity whether containing the Stock or not is connected with the barrel by two pieces of metal & moved

perpendicularly or obliquely on an axis. The work from the barrel is prevented by two shoulder marks, muzzle, which enter two notches in the side pieces of metal. The rear parts of these shoulders, as also the rear parts of these notches are formed to a curve deviated from the axis, on which the receiver bears. — The rear extremity of the receiver is formed in the same way, that it may make a good joint with the wood work of the stock.

A screw may pass thro' the rear extremities of the side pieces of metal serving to connect them with the stock. Under the barrel are loops, as for common guns, by which it is fastened to the stock. Under the fore part of the barrel is a dove tailed rib in military guns with a hole near each extremity for receiving a pin attached to a spring on a bayonet, by which the bayonet is kept in its place either when fixed to the end of the barrel or when retracted. — The bayonet has instead of a socket a handle in which is a dove tailed groove corresponding to the rib of the barrel.

In case of the gun being whole stocked the rib must be shorter, & no provision made for retracting the Bayonet.

Fig. 1. — The chamber of solid metal or one metal screwed or let into another. — This chamber or receiver may be conical, cylindrical or otherwise & the muzzle of the receiver may be arched perpendicularly from top to bottom, making a curve whose center is at twelve, or be cut obliquely, so that its end may be a tangent to the lower part of the curve at 32.

Fig. 2. — The cock which may be made in any elegant form.

3. — The hammer, the striking of

which may be concealed.

53

4. — The touch-hole when made up the top, it enters at the centre of the chamber. The touch-hole may be made at the side & the lock be put on the outside of handsomely finished pieces. —

5. — The trigger & trigger-bolt in one. —

6. — The main spring which may be made in various ways. —

7. — The main spring which answers also for the hammer-spring fastened to the receiver. —

8. — The trigger-spring. —

9. — Prevents, which are solid shal-
ders, or may be screwed on to the chamber-piece &
which by entering into the notches of the side-pieces
or supporters 16. 16. prevent the recoil from the Barrel
while discharging; for if the chamber be made very
tight it will be difficult to shut it after a few dis-
charges, in consequence of its expansion. — This precau-
tion was therefore found necessary and answers com-
pletely. —

10. Elevator or spring, which throws
up the chamber or receiver. —

11. — Catch spring which passes thro
the stock. —

12. — The axis or centre on which
the receiver or chamber moves up & down. —

13. — Bottom of the chamber. —

14. — Right supporter. —

15. — Left supporter, by which the
receiver is connected with the Barrel when elevated. —

16. — The supporters. —

17. — Screw for Hammer. —

18. — Guard which is fastened to

the barrel.

19. - One of the sights.

20. - Screw by which the supporters are
fashioned to the barrel. -

21. - Gun stock. -

22. - Joint between the chamber & stock.

23. - Entrance of the chamber which may
be well-formed at its hinder part to receive with ease
the Ball or shot when projected from the chamber.
The barrel may be rifled or smooth-bored. -

24. - The powder chamber. -

25. - Place for the Ball or shot, chargeable
either by cartridge or flask.

26. - One piece of metal over which may
be a guard any other catch either on the side, or
a bolt on the side or a bolt formed by the trigger
guard may be substituted. -

27. - Screw for elevator. -

28. - Screw-pin, by which the left supporter
is connected with the stock. -

29. - Screws by which the ground is fastened
to the stock. -

30. -
